UNITED STATES PATENT OFFICE.

LOUIS O. SUTTON, OF WILMINGTON, DELAWARE.

GAME APPARATUS.

1,031,395.

Specification of Letters Patent.

Patented July 2, 1912.

Application filed July 20, 1911. Serial No. 639,548.

To all whom it may concern:

Be it known that I, LOUIS O. SUTTON, a citizen of the United States, residing at Wilmington, in the county of Newcastle and State of Delaware, have invented certain new and useful Improvements in Game Apparatus, of which the following is a specification.

My invention relates to improvements in game apparatus, an object of the invention being to provide an improved game table designed especially for playing the game of baseball, and which will automatically record on the board by means of electric lights, the representation of a base runner moving along the base lines, and at the several bases.

A further object is to provide an improved dial containing arms adapted to be moved in accordance with the operation of the ball operated contacts, whereby the electric lights under the base lines and at the bases are controlled in accordance with the base hit values of the contacts operated to give the appearance of base runners moving from base to base, as is customary in the ordinary game of baseball.

A further object is to provide an improved arrangement of arms, releasing means and contacts on the dial, together with an improved arrangement of electromagnets controlling the operation and limiting the movement of said arms, whereby the movement of the arms properly controls the operation of the lights in accordance with the hit values of the several ball operated contacts.

A further object is to provide an improved table indicating thereon the representation of a baseball field with the base lines transparent, and electric lights under the base lines and at the bases, said lights included in circuits which are closed by the movement of cue balls in accordance with the movement of the latter.

A further object is to provide a game board or table having a cushion against which cue balls are adapted to be driven by means of the ordinary cue, and provide electric contacts in circuit with electric lights, said contacts moved together by the ball as it is deflected from the cushion, so as to cause the illumination of certain of said lights.

A further object is to provide a game apparatus of this character in which openings are provided in the board or table through which the cue balls pass when said balls fail to engage the contacts above referred to, and in which position said balls record outs in the game of baseball, and provide below said openings, alleys joining a common alley for the care of the balls passing through said openings, said openings being located on the field at the positions ordinarily occupied by the players.

With these and other objects in view, the invention consists in certain novel features of construction and combinations and arrangements of parts, as will be more fully hereinafter described and pointed out in the claims.

In the accompanying drawings: Figure 1, is a plan view illustrating my improvements. Fig. 2, is a view in longitudinal section on the line 2—2 of Fig. 1. Fig. 3, is a view in transverse section on the line 3—3 of Fig. 1. Fig. 4, is an inverted longitudinal section on the line 4—4 of Fig. 2. Fig. 5, is a sectional plan view on the line 5—5 of Fig. 2. Fig. 6, is a plan view on an enlarged scale of the electric circuit controlling dial. Fig. 7, is a view in vertical section through the dial and its coöperating mechanism. Fig. 8, is a diagrammatic view of the electric circuits. Fig. 9, is an enlarged fragmentary sectional view illustrating one of the ball operating platforms and its mounting. Fig. 10, is a view at right angles to Fig. 9. Fig. 11, is a perspective view of one of the platforms. Fig. 12, is a perspective view of one of the platform supporting levers. Fig. 13, is a perspective view of one of the contact arms. Fig. 14, is a view in section illustrating the contact arm releasing mechanism. Fig. 15, is a view in section at right angles to Fig. 14, and Fig. 16, shows an ordinary cue and three cue balls with which the game is played.

The game apparatus comprises a box-like body having a bottom 1, sides 2, 2, ends 3, and a top 4, the top 4 constituting the field which is located a distance below the upper edges of the sides and ends to confine the cue balls on the field during the playing of the game.

The body is preferably supported on suit-

able legs 5, and is of approximately the same size as an ordinary billiard or pool table. On the top or table 4, transparent strips 6 are inserted representing the base 5 lines of ordinary baseball diamonds, which connect transparent squares 7 which I shall term "bases". Beneath each base, and beneath the transparent strips 6, are electric lights 8, and for convenience of description 10 I shall hereinafter refer to these lights as "base line" lights and "base" lights. At one end of the table is a deflecting cushion 9 which is of general heart shape cut under as shown more particularly in Fig. 2, and 15 adapted to be struck by an ordinary cue ball 16 when operated by an ordinary cue 17 illustrated in Fig. 16.

Back of the representation of the diamond, and at points which would ordinarily 20 be occupied by players on an ordinary baseball field, openings 10 are provided in the top 4, blocks 11 being located back of said openings to serve as abutments, and the walls of said openings removed from said 25 blocks, being beveled or inclined to more effectually direct the cue balls into the openings. Below the several openings 10, channels or passages 12 are provided which incline downwardly to a common passage 13, 30 and the latter discharges through an opening 14, so that any cue ball which may fall through any of said openings will pass into a receptacle 15 provided for their reception outside of the table.

35 To control the lights above referred to, and in fact to control the entire operation of the device, a dial 18 is supported in a suitable box 19 below table 4, and is provided with a central opening 20, through 40 which a vertical shaft 21 projects. This shaft 21 is supported in a bracket 22 fixed to a base 23. On this base 23, a motor 24 is supported, and the shaft of this motor drives a worm 25 which transmits motion to a 45 worm wheel 26 on shaft 21. The upper end of this shaft 21 is reduced in diameter and made rectangular in cross section to receive thereon a series of disks 27, having angular openings so as to compel the disks to turn 50 with the shaft. Each of these disks 27 is provided on its upper face with a circular groove 28 to receive the ring like end 29 of a contact arm, and as there are a plurality of these contact arms having different functions, they will be hereinafter given separate reference characters.

55 It is to be understood that the rings 29 are thicker than the grooves 28 are deep, so that the rings have frictional engagement 60 with the disks above and below. On top of the series of rings 29, a disk 30 is located, and the extreme upper end of shaft 21 is screw-threaded for the reception of a nut 31 which exerts downward pressure on a spring 32 bearing on disk 30. By adjusting the

nut 31, the frictional engagement of the several rings 29 may be varied so as to exactly suit conditions.

The contact arms above referred to, constitute four sets of varying lengths, the 70 shorter arms 33 which I term "one base hit" arms being lowermost when in normal position. The next series of arms 34 above 75 I term "two base hit" arms. The third series of arms 35, I term "three base hit" 75 arms, and the single uppermost arm 36, I term "home run" arm. It is to be understood that in operation, all of these arms move throughout the greater portion of the dial in the same horizontal plane, but at 80 their starting point are at different elevations, so that the arm of any of said series may move out ahead of the others. To thus position the arms, inclined platforms 37 are provided, upon which the outer ends of the 85 arms 34, 35, and 36 ride as they near the end of their movement.

It is to be understood that the first base 90 hit arms 33 are the shortest, the two base hit arms 34 slightly longer, the three base hit 95 arms 35 slightly longer than the arms 34, and the home run arm 36 the longest for a purpose which will hereinafter appear.

It is to be understood that all of the arms 100 are of metal, and good electric conductors. 95 The first base hit arms are of one piece, while the other arms comprise two members pivotally connected as shown at 38, and having springs 39 exerting downward pressure on the arms to normally press them into 100 tight engagement with the dial.

On the face of the dial, circular contacts 40 are provided, which are in an electric circuit with the motor 24, and on the several 105 platforms 37, similar contacts 41 are provided in circuit with the motor, so that the several arms maintain the circuit closed with the motor until they reach the end of their movement. Circular contacts 42 are also provided on the face of the dial, which are 110 in circuit with the lights 8. Three upwardly spring-pressed plungers 43, 44, and 45, respectively normally project through and above the surface of dial 18, and these plungers I shall term "first base" plungers, 115 "second base" plunger, and "third base" plunger respectively.

At the starting point of the several arms, four pivoted catches 46, 47, 48, and 49 respectively are mounted, and control the operation of the several arms. For convenience of description, these catches will be hereinafter referred to as "one base hit" catch, "two base hit" catch, "three base hit" catch, and "home run" catch respectively.

120 Figs. 14 and 15 illustrate on an enlarged scale the one base hit catch 46. The catch is so shaped that when it is in its normal position, one of the arms lies in position be- 125

tween the two forks of the catch ready for release, and when one arm is released, the second one will be held back until the catch moves upwardly to normal position. When 5 the pressure of the spring 50 on a plunger 51 connected to said catch will be sufficient on rebound to move the catch far enough to allow the next arm to move into set position, said next arm will be permitted to move into 10 the place of the arm just released.

The plungers of the several catches are controlled by electro-magnets 52, and the plungers 43, 44, and 45 are controlled by electro-magnets 53. Between the starting 15 point and the first base plunger 43, curved contacts 54 are provided in the face of the dial, which terminate short of the first base plunger 43, and are located radially between said plunger 43 and the center of the dial.

20 Outside of the plunger 43, and extending from a point in advance of said plunger to a point in advance of plunger 44, are two electric contacts 55. In an arc outside of contacts 55, and extending from a point in 25 advance of plunger 44 to a point in advance of plunger 45, are two contacts 56, and similar contacts 57 extend from a point in advance of plunger 45 to a point beyond the same. - The home run arm 36 is sufficiently 30 long to engage all of these contacts 54, 55, 56, and 57 in regular order, and as all of these contacts are inclined in the electric circuit which controls the several magnets 53 operating plungers, the several plungers will 35 remain depressed throughout the movement of the home run arm 36, allowing the latter to make a complete turn of the dial.

The three base hit arms 35 are sufficiently long to engage contacts 54, 55, and 56, but 40 not long enough to engage contacts 57, hence when said arms ride off of the ends of contacts 56, the electro-magnet 53 below plunger 45 will be open circuited, so that the plunger 45 will rise and stop the three base hit arms.

45 The two base hit arms will engage contacts 54, and 55, only, while the one base hit arms are long enough to engage contacts 54 only. It will also be noted that the plungers 43, 44, and 45 are not spaced an equal distance apart, but have varying spacing between them. In other words, it will be noted that the plunger 43 is spaced a relatively long distance from the starting point, the space between plungers 44 and 43 being

55 less than that between plunger 43 and the starting point, and the space between plungers 43 and 45 being less than the space between plungers 43 and 44. This is to permit a base runner which is on one of the bases 60 to advance two bases when a one base hit is made in the game, so that the apparatus carries out the normal results which take place upon the making of base hits in an ordinary ball game.

65 In the sides 2, and ends 3 of the box like

body, tracks 58 are provided for the reception and passage of cue balls 16, and said passages are inclined to a pocket 59 at the end of the table, so that these balls which do not enter the openings 10, are returned 70 for further use. Beside these tracks 58, vertically movable platforms are located, and are given separate reference characters for clearness of description.

The sides 2 at points in line with the first and third base lines of the diamond, illustrated by the transparent sections 6, are curved or projected inwardly as shown at 60, so that balls which do not come inside of the lines 6, in other words foul balls, are deflected back into the field. Between these inwardly projecting portions 60 and the playing end of the field, and at both sides of the table, are two platforms, and at the player end of the table, are three of these 85 platforms, making seven in all.

The first two platforms, or those adjacent to the representation of a diamond, I give reference characters 61 and 62 respectively, and these platforms are what I term "one 90 base hit" platforms. The adjacent platforms 63 and 64, which extend from the ends of platforms 61 and 62 to the end of the table, I term "two base hit" platforms. The outside platforms 65 and 66, at the end 95 of the table, I term "three base hit" platforms, and the central platform 67 at the end of the table, I term "home run" platform. These platforms 61, 62, 63, 64, 65, 66, and 67, are all constructed precisely alike 100 as shown most clearly in Figs. 9 and 10. Each platform is provided with bracket arms 68, which are secured to a knife edge 69, the latter is mounted in the grooved end of a lever 70. Lever 70 is provided between 105 its ends with a knife edge 71, mounted in a supporting bar 72, and the inner end of said lever is screw-threaded for the reception of a weighted nut 73. By adjusting this nut 73, the platform may be nicely balanced so that the weight of the cue ball will cause the same to move downwardly, and direct the ball onto the track 58.

Various ways of closing the electric circuit through the motor 24 and the proper 115 magnet 52 may be provided, a simple structure being illustrated in Fig. 9, in which the contacts 74 are brought together by the downward movement of the platform.

75, represents the line wires. The several 120 contacts below the platforms 61, 62, 63, 64, 65, 66, and 67 are included in an electric circuit with one of the line wires, and their proper magnet 52, all of said magnets 52 being in circuit through the motor 24 to the 125 other of said line wires as clearly shown in the diagram, Fig. 8. As soon as any of the platforms are depressed by means of the cue ball, the motor will be instantly started. As soon as the motor starts, the proper 130

4
magnet 52 will have released the proper arm, so that the arm will close the magnet contacts 40, and as the latter are included in an electric circuit between the line wires 5 and the motor, they will keep the motor in operation until said arm again reaches its starting point. The contacts 54, 55, 56, and 57 are included in an electric circuit with the three magnets 53, controlling the plun- 10 gers 43, 44, and 45, so that when these contacts are closed by means of the arms, the plungers 43, 44, and 45 will be depressed. Contacts 42 are also connected in electric circuit with the lights, and line wires, where- 15 by the arms serve to close the circuits to the respective lights. The diagram shown in Fig. 8 clearly sets forth these circuits and the operation of the device through the medium of said electric power transmission, 20 will now be described.

The player standing at one end of the table positions a cue ball on the table, and with the cue impels the ball against the cushion 9, from which it is deflected. By 25 reason of the peculiar shape of this cushion, the game becomes a very scientific one. Each inning the player starts with three balls, and until these balls disappear through the pockets 10, which register outs, he continues 30 to play.

We will assume that the first ball finds its way into one of the openings 10. We will next assume that the second ball moves onto the first base hit platform 61. As 35 soon as this platform is depressed by the ball, the motor is started. At the same time, the proper magnet 52 operates catch 46 to release one of the one base hit arms 33. As soon as this arm is released, the 40 frictional contact of the disks 27 will compel this arm to turn with shaft 21. As the arm moves, it closes the magnet contacts 40, and the light contacts 42 to cause the lights between the home plate and first base 45 to light up in regular succession. This movement of the arm also closes the circuit between the contacts 54 to energize the magnets 53 and depress the plungers 43, 44, and 45. As the contacts 54, however, terminate before the arm reaches the plunger 43, these several plungers will be elevated by their springs, so that the first base hit arm 50 will be stopped by the plunger 43, but will maintain lighted the light at the first base. 55 We will next suppose the player operates the ball so that it again depresses the same platform 61. As soon as this happens, the second arm 33 will begin its movement. It operates precisely as the above described 60 arm with the exception that as soon as it closes the circuit between contacts 54, the arm which has been held by the plunger 43, will move with the shaft 21, and as the distance between plungers 43 and 44 is less 65 than the distance between the plunger 43

and the starting point, the arm first referred to will have passed plunger 44 before the arm last referred to reaches plunger 43, so that the first named arm will move on until it is stopped by plunger 45. 70 The lights on the table will then show a man on first and a man on third base. We will suppose that the next ball operated falls into a pocket 10, which will make two out. We will assume that the next cue 75 ball is manipulated so that it depresses the two base hit platform 64. When this takes place, the two base hit arm is released by its catch 47. As soon as this arm closes the circuit between the contacts 54, the plun- 80 gers 43, 44, and 45 will all be depressed, so that the arms held by plungers 43, and 45 will begin to turn. As they move, the lights under the base lines will be illuminated, so that the field will give the appearance of base runners running from third 85 home, from first toward second, and from home toward first. As the second base hit arm is long enough to reach the contacts 55, the several plungers 43, 44, and 45 will remain depressed until the arm rides off the contacts 55. This will give sufficient time 90 for the arm which was held by the plunger 43 to pass the plunger 45, so that both men which were on base will travel home, while 95 the two base hit arm will be stopped by plunger 44. Thus, the player has scored two runs, and has a man on second base. If the next ball hit passes into one of the openings 10, it will make three out, and the 100 inning is over for this player.

It will be noted that innumerable combinations may take place in accordance with the platform operated by the cue ball. In any event, such combinations will be such 105 as normally take place on a ball field in accordance with the value of the hits. In other words, a single will advance a man on the bases two bases, a double, a triple or a home run will clean the bases, and this 110 is brought about by reason of the spacing of the several plungers 43, 44, and 45, and the length of the several arms which close the circuits through the several contacts 54, 55, 56, and 57, respectively. In order to 115 enable these arms to pass each other, the two base hit, three base hit, and home run arms ride up the platforms 37, and assume different elevations, which is permitted by the hinged sections of said arms. This 120 movement up the inclines, of course, elevates the arms from the contacts 40 but the circuit with the motor is maintained closed by reason of the contacts 41. When the magnets 52 are operated, and the arms move 125 off of their platforms, the springs 39 force the arms flat down upon the dial, so that it closes the several contacts as above explained.

Various slight changes might be made in 130

the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms constructed to close certain of said contacts, and the longer of said arms only constructed to close all of said contacts, substantially as described.

2. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms constructed to close certain of said contacts, the longer of said arms only constructed to close all of said contacts, all of said longer arms comprising two sections hinged together, and springs exerting downward pressure on said arms, substantially as described.

3. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms constructed to close certain of said contacts, and the longer of said arms only constructed to close all of said contacts, a motor driven shaft having an angular end, disks having angular openings positioned on said shaft, said disks having circular grooves therein, rings on the ends of said arms positioned in said grooves and thicker than the depth of the groove, a spring exerting pressure on said disks and rings, and a nut screwed onto said shaft against said spring, substantially as described.

4. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms

constructed to close certain of said contacts, the longer of said arms only constructed to close all of said contacts, all of said longer arms comprising two sections hinged together, springs exerting downward pressure on said arms, a motor driven shaft having an angular end, disks having angular openings positioned on said shaft, said disks having circular grooves therein, rings on the ends of said arms positioned in said grooves and thicker than the depth of the groove, a spring exerting pressure on said disks and rings, and a nut screwed onto said shaft against said spring, substantially as described. 70

5. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms constructed to close certain of said contacts, and the longer of said arms only constructed to close all of said contacts, spring-pressed plungers projecting through said dial, spaced different distances apart, and adapted to be engaged by and limit the movement of said arms, electro-magnets controlling the movement of said plungers, and the said contacts on said dial engaged by the said arms respectively for controlling the operation of said last-mentioned magnets, substantially as described. 80

6. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms constructed to close certain of said contacts, the longer of said arms only constructed to close all of said contacts, all of said longer arms comprising two sections hinged together, springs exerting downward pressure on said arms, spring-pressed plungers projecting through said dial, spaced different distances apart, and adapted to be engaged by and limit the movement of said arms, electro-magnets controlling the movement of said plungers, and the said contacts on said dial engaged by the said arms respectively for controlling the operation of said last-mentioned magnets, substantially as described. 90

7. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms

arms at the starting point, all of said arms constructed to close certain of said contacts, and the longer of said arms only constructed to close all of said contacts, a motor driven shaft having an angular end, disks having angular openings positioned on said shaft, said disks having circular grooves therein, rings on the ends of said arms positioned in said grooves and thicker than the depth 10 of the groove, a spring exerting pressure on said disks and rings, a nut screwed onto said shaft against said spring, spring-pressed plungers projecting through said dial, spaced different distances apart, and 15 adapted to be engaged by and limit the movement of said arms, electro-magnets controlling the movement of said plungers, and the said contacts on said dial engaged by the said arms respectively for controlling 20 the operation of said last-mentioned magnets, substantially as described.

8. A circuit controlling mechanism for an apparatus of the character described, comprising a dial, electric contacts on the surface of said dial, a plurality of arms mounted to turn on said dial, said arms comprising sets of different lengths, platforms elevating the longer arms above the shorter arms at the starting point, all of said arms 25 constructed to close certain of said contacts, the longer of said arms only constructed to close all of said contacts, all of said longer arms comprising two sections hinged together, springs exerting downward pressure on said arms, a motor driven shaft having an angular end, disks having angular openings position on said shaft, said disk having circular grooves therein, rings on the ends of said arms positioned 30 in said grooves, and thicker than the depth of the groove, a spring exerting pressure on said disks and rings, a nut screwed onto said shaft against said spring, spring-pressed plungers projecting through said 35 dial, spaced different distances apart, and adapted to be engaged by and limit the movement of said arms, electro-magnets controlling the movement of said plungers, and the said contacts on said dial engaged 40 by the said arms respectively for controlling the operation of said last-mentioned magnets, substantially as described.

9. A game apparatus, comprising a field, transparent base lines on said field, electric 55 lights below the said base lines normally extinguished, a dial, contacts on said dial arms mounted to turn on the dial to engage the contacts and close the electric circuits to said lights, devices normally holding said arms against movement, and contact closing platforms on the field constructed to close electric circuits to release said arm holding means, substantially as described.

10. A game apparatus, comprising a field, 60 transparent base lines on said field, electric

lights below the said base lines normally extinguished, a dial, contacts on said dial, arms mounted to turn on the dial to engage the contacts and close the electric circuits to said lights, devices normally holding said arms against movement, and contact closing platforms on the field constructed to close electric circuits to release said arm holding means, substantially as described. 70

11. A game apparatus comprising a field, transparent base lines on said field, electric 80 lights below said base lines normally extinguished, a motor, a shaft driven by the motor, a dial, a plurality of arms frictionally connected with said shaft and adapted to move about the face of the dial, contacts 85 on said dial included in a circuit with said motor, contacts on said dial included in circuits with said lights, said arms adapted to close said circuits, and means for normally holding said arms against movement, 90 substantially as described.

12. A game apparatus comprising a field, transparent base lines on said field, electric lights below said base lines normally extinguished, a motor, a shaft driven by the 95 motor, a dial, a plurality of arms frictionally connected with said shaft and adapted to move about the face of the dial, contacts on said dial included in a circuit with said motor, contacts on said dial included in 100 circuits with said lights, said arms adapted to close said circuits, means holding said arms against movement, electro-magnets constructed to operate said holding means to release the arms, and platforms on the 105 field controlling the operation of said magnets, substantially as described.

13. A game apparatus comprising a field, transparent base lines on said field, electric 110 lights below said base lines normally extinguished, a motor, a shaft driven by the motor, a dial, a plurality of arms frictionally connected with said shaft and adapted to move about the face of the dial, contacts on said dial included in a circuit 115 with said motor, contacts on said dial included in circuits with said lights, said arms adapted to close said circuits, said arms of varying lengths, a plurality of catches normally holding said arms against movement, 120 electro-magnets adapted to release said arms, and platforms on the field controlling the operation of said magnets, substantially as described.

14. A game apparatus comprising a field, 125 transparent base lines on said field, electric lights below said base lines normally extinguished, a motor, a shaft driven by the motor, a dial, a plurality of arms frictionally connected with said shafts and adapted 130

- to move about the face of the dial, contacts on said dial included in a circuit with said motor, contacts on said dial included in circuits with said lights, said arms adapted to close said circuits, said arms of varying lengths; a plurality of catches normally holding said arms against movement, electro-magnets adapted to release said arms, platforms on the field controlling the operation of said magnets, inclined platforms on the said dial supporting the longer of said arms at their starting point, whereby any of said arms may move on the dial in advance of the others, substantially as described. 10
15. A game apparatus, comprising a field, transparent base lines on said field, electric lights below said base lines normally extinguished, a dial, contacts on said dial, arms mounted to turn on the dial to engage the contacts and close the electric circuits to said lights, devices normally holding said arms against movement, and contact closing platforms on the field constructed to close electric circuits to release said arm holding means, and electrically controlled means on said dial limiting the movement of said arms, substantially as described. 20
25. 16. A game apparatus, comprising a field, transparent base lines on said field, electric lights below the said base lines normally extinguished, a dial, contacts on said dial, arms mounted to turn on the dial to engage the contacts and close the electric circuits to said lights, devices normally holding said arms against movement, and contact closing platforms on the field constructed to close electric circuits to release said arm holding means, said arm holding means comprising pivoted spring held catches, electro-magnets 30 adapted to move said catches in one direction, and electrically controlled means on said dial limiting the movement of said arms, substantially as described. 35
40. 17. A game apparatus comprising a field, transparent base lines on said field, electric lights below said base lines normally extinguished, a motor, a dial, a shaft driven by the motor, a plurality of arms frictionally connected with said shaft and adapted to move about the face of the dial, contacts on said dial included in a circuit with said motor, contacts on said dial included in circuits with said lights, said arms adapted to close said circuits, means for normally holding said arms against movement, and electrically controlled means on said dial limiting the movement of said arms, substantially as described. 45
50. 18. A game apparatus comprising a field, transparent base lines on said field, electric lights below said base lines normally extinguished, a motor, a dial, a shaft driven by the motor, a plurality of arms frictionally connected with said shaft and adapted to move about the face of the dial, contacts 55 on said dial included in a circuit with said motor, contacts on said dial included in circuits with said lights, said arms adapted to close said circuits, means for normally holding said arms against movement, and electrically controlled means on said dial limiting the movement of said arms, substantially as described. 60
65. 19. A game apparatus comprising a field, transparent base lines on said field, electric lights below said base lines normally extinguished, a motor, a dial, a shaft driven by the motor, a plurality of arms frictionally connected with said shaft and adapted to move about the face of the dial, contacts on said dial included in a circuit with said motor, contacts on said dial included in circuits with said lights, said arms adapted to close said circuits, means holding said arms against movement, electro-magnets constructed to operate said holding means to release the arms, and platforms on the field controlling the operation of said magnets, and electrically controlled means on said dial limiting the movement of said arms, substantially as described. 70
75. 20. A game apparatus comprising a field, transparent base lines on said field, electric lights below said base lines normally extinguished, a motor, a dial, a shaft driven by the motor, a plurality of arms frictionally connected with said shaft and adapted to move about the face of the dial, contacts on said dial included in a circuit with said motor, contacts on said dial included in circuits with said lights, said arms adapted to close said circuits, said arms of varying lengths, a plurality of catches normally holding said arms against movement, electro-magnets adapted to release said arms, platforms on the field controlling the operation of said magnets, and electrically controlled means on said dial limiting the movement of said arms, substantially as described. 80
85. 21. A game apparatus comprising a field, transparent base lines on said field, electric lights below said base lines normally extinguished, a dial, contacts on said dial, arms mounted to turn on the dial to engage the contacts and close the electric circuits to said lights, devices normally holding said arms against movement, contact closing platforms on the field constructed to close electric circuits to release said arm holding means, spring-pressed plungers projecting above the surface of said dials, and spaced different distances apart, electro-magnets 90

constructed to move said plungers out of the path of movement of the arms, and contacts on said dial closed by said arms controlling the movement of said last-mentioned magnets, substantially as described.

22. A game apparatus, comprising a field, transparent base lines on said field, electric lights below the said base lines normally extinguished, a dial, contacts on said dial, 10 arms mounted to turn on the dial to engage the contacts and close the electric circuits to said lights, devices normally holding said arms against movement, and contact closing platforms on the field constructed to close electric circuits to release said arm holding 15 means, said arm holding means comprising pivoted spring held catches, electro-magnets adapted to move said catches in one direction, spring-pressed plungers projecting above the surface of said dials and spaced 20 different distances apart, electro-magnets constructed to move said plungers out of the path of movement of the arms, and contacts on said dial closed by said arms controlling the movement of said last-mentioned 25 magnets, substantially as described.

23. A game apparatus comprising a field, transparent base lines on said field, electric lights below said base lines normally extinguished, a motor, a dial, a shaft driven by 30 the motor, a plurality of arms frictionally connected with said shaft and adapted to move about the face of the dial, contacts on said dial included in a circuit with said 35 motor, contacts on said dial included in circuits with said lights, said arms adapted to close said circuits, means for normally holding said arms against movement, spring-pressed plungers projecting above the surface of said dials and spaced different distances apart, 40 electro-magnets constructed to move said plungers out of the path of movement of the arms, and contacts on said dial closed by said arms controlling the movement of said last-mentioned 45 magnets, substantially as described.

24. A game apparatus comprising a field, transparent base lines on said field, electric lights below said base lines normally extinguished, a motor, a dial, a shaft driven by 50 the motor, a plurality of arms frictionally connected with said shaft and adapted to move about the face of the dial, contacts on said dial included in a circuit with said 55 motor, contacts on said dial included in circuits with said lights, said arms adapted to close said circuits, electro-magnets normally holding said arms against movement, platforms on the field controlling the operation 60 of said magnets, spring-pressed plungers projecting above the surface of said dials and spaced different distances apart, electro-magnets constructed to move said plungers out of the path of movement of the arms, 65 and contacts on said dial closed by said arms

controlling the movement of said last-mentioned magnets, substantially as described.

25. A game apparatus comprising a field, transparent base lines on said field, electric lights below said base lines normally extinguished, a motor, a dial, a shaft driven by 70 the motor, a plurality of arms frictionally connected with said shaft and adapted to move about the face of the dial, contacts on said dial included in a circuit with said motor, contacts on said dial included in circuits with said lights, said arms adapted to close said circuits, said arms of varying lengths, a plurality of catches normally holding said arms against movement, electro-magnets adapted to release said arms, 75 platforms on the field controlling the operation of said magnets, spring-pressed plungers projecting above the surface of said dials and spaced different distances apart, 80 electro-magnets constructed to move said plungers out of the path of movement of the arms, and contacts on said dial closed by 85 said arms controlling the movement of said last-mentioned magnets, substantially as described. 90

26. A game apparatus comprising a field, transparent base lines on said field, electric lights below said base lines normally extinguished, a motor, a dial, a shaft driven by 95 the motor, a plurality of arms frictionally connected with said shaft and adapted to move about the face of the dial, contacts on said dial included in a circuit with said motor, contacts on said dial included in circuits with said lights, said arms adapted to close said circuits, said arms of varying lengths, a plurality of catches normally holding said arms against movement, electro-magnets adapted to release said arms, 100 platforms on the field controlling the operation of said magnets, inclined platforms on said dial supporting the longer of said arms at their starting point, whereby any of said arms may move on the dial in advance of the others, spring-pressed plungers projecting above the surface of said dials and spaced different distances apart, electro-magnets constructed to move said plungers 105 out of the path of movement of the arms, and contacts on said dial closed by said arms controlling the movement of said last-mentioned magnets, substantially as described. 110

27. A game apparatus comprising a field, transparent base lines on said field, electric lights below said base lines normally extinguished, a dial, a shaft projecting through 115 said dial, a motor constructed to turn said shaft, contacts on said dial included in electric circuits with the said lights, a plurality of arms frictionally engaging said shaft, said arms of four different lengths, the shorter three constituting first base hit arms, 120 the next longer two constituting two base 125 arms.

hit arms, the next longer two constituting two base hit arms, and the longest arm constituting a home run arm, plungers in the path of movement of said arms, electro-magnets controlling said plungers, and contacts through which the circuit is closed by the respective arms controlling the movement of said plungers, said contacts spaced varying distances from the center of said dial, whereby all of them are engaged by the home run arm only, and electric means controlling the release of said arms, substantially as described.

31. A circuit controlling mechanism for an apparatus of the character described, comprising a dial, a rotary shaft, contacts on the dial, arms of different lengths in frictional engagement with said shaft and adapted to engage the said contacts, and means normally holding said arms against movement, substantially as described. 70

32. A circuit controlling mechanism for an apparatus of the character described, comprising electric contacts, a rotary shaft, a plurality of arms frictionally engaging said shaft and constructed to engage certain of said contacts, and means normally holding said arms against movement, substantially as described. 75

33. A circuit controlling mechanism for an apparatus of the character described, comprising electric contacts, a rotary shaft, a plurality of arms frictionally engaging said shaft and constructed to engage certain of said contacts, said arms of different lengths, and the longer of said arms only constructed to engage all of said contacts, substantially as described. 80

34. A circuit controlling mechanism for an apparatus of the character described, comprising a dial, electric contacts on the surface of said dial, and a plurality of arms mounted to turn on said dial and adapted to engage certain of said contacts, means holding the arms against movement with the shaft, and electro-magnets adapted to operate said holding means to release the arms one at a time, substantially as described. 95

35. A circuit controlling mechanism for an apparatus of the character described, comprising a dial, a rotary shaft, contacts on the dial, and arms of different lengths in frictional engagement with said shaft and adapted to engage the said contacts, means holding the arms against movement with the shaft, and electro-magnets adapted to operate said holding means to release the arms one at a time, substantially as described. 100

36. A circuit controlling mechanism for an apparatus of the character described, comprising electric contacts, a rotary shaft, a plurality of arms frictionally engaging said shaft and constructed to engage certain of said contacts, means holding the arms against movement with the shaft, and electro-magnets adapted to operate said holding means to release the arms one at a time, substantially as described. 115

37. A circuit controlling mechanism for an apparatus of the character described, comprising electric contacts, a rotary shaft, a plurality of arms frictionally engaging said shaft and constructed to engage certain of said contacts, said arms of different 120

130

hit arms, the next longer two constituting two base hit arms, and the longest arm constituting a home run arm, plungers in the path of movement of said arms, electro-magnets controlling said plungers, and contacts spaced varying distances from the center of said dial, whereby all of them are engaged by the home run arm only, and electric means controlling the release of said arms, substantially as described.

28. A game apparatus comprising a field, transparent base lines on said field, electric lights below said base lines normally extinguished, a dial, a shaft projecting through said dial, a motor constructed to turn said shaft, contacts on said dial included in electric circuits with the said lights, a plurality of arms frictionally engaging said shaft, said arms of four different lengths, the shorter three constituting first base hit arms, the next longer two constituting two base hit arms, the next longer two constituting two base hit arms, and the longest arm constituting a home run arm, plungers in the path of movement of said arms, electro-magnets controlling said plungers, contacts through which the circuit is closed by the respective arms controlling the movement of said plungers, said contacts spaced varying distances from the center of said dial, whereby all of them are engaged by the home run arm only, and electric means controlling the release of said arms, said controlling means comprising pivoted catches, electro-magnets controlling the operation of said catches, and contact closing ball operated platforms on said field controlling the circuits to said last-mentioned magnets, substantially as described. 80

29. A game apparatus comprising a field, transparent base lines on said field, electric lights below the base lines normally extinguished, circuit closing means controlling the illumination of said lights, downwardly movable platforms on said field controlling the said circuit closing means, brackets secured to the bottom of said platforms, a knife edge bearing connecting said brackets, a lever having a knife edge bearing between its ends, and a knife edge recess at one end to receive said first-mentioned bearing, screw-threads on the opposite end of said lever, and an adjustable weight screwed onto said lever, whereby said platform may be adjusted to properly balance, substantially as described. 90

30. A circuit controlling mechanism for an apparatus of the character described, comprising a dial, electric contacts on the surface of said dial, a plurality of arms mounted to turn on said dial and adapted to engage certain of said contacts, means holding the arms against movement with the shaft, and electro-magnets adapted to operate said holding means to release the arms one at a time, substantially as described. 100

31. A circuit controlling mechanism for an apparatus of the character described, comprising a dial, a rotary shaft, contacts on the dial, and arms of different lengths in frictional engagement with said shaft and adapted to engage the said contacts, means holding the arms against movement with the shaft, and electro-magnets adapted to operate said holding means to release the arms one at a time, substantially as described. 110

32. A circuit controlling mechanism for an apparatus of the character described, comprising electric contacts, a rotary shaft, a plurality of arms frictionally engaging said shaft and constructed to engage certain of said contacts, means holding the arms against movement with the shaft, and electro-magnets adapted to operate said holding means to release the arms one at a time, substantially as described. 120

33. A circuit controlling mechanism for an apparatus of the character described, comprising electric contacts, a rotary shaft, a plurality of arms frictionally engaging said shaft and constructed to engage certain of said contacts, said arms of different 125

130

hit arms, the next longer two constituting two base hit arms, and the longest arm constituting a home run arm, plungers in the path of movement of said arms, electro-magnets controlling said plungers, and contacts spaced varying distances from the center of said dial, whereby all of them are engaged by the home run arm only, and electric means controlling the release of said arms, substantially as described.

lengths, and the longer of said arms only constructed to engage all of said contacts, means holding the arms against movement with the shaft, and electro-magnets adapted to operate said holding means to release the arms one at a time, substantially as described.

In testimony whereof I have signed my name to this specification in the presence of two subscribing witnesses.

LOUIS O. SUTTON.
